(57) **CLAIM**

The ornamental design for a combined ceiling fan housing and light kit, as shown and described.

DESCRIPTION

FIG. 1 is a bottom perspective view of a combined ceiling fan housing and light kit showing my new design;

FIG. 2 is a top perspective view thereof;

FIG. 3 is front elevational view thereof, the rear elevational view thereof, the left side elevational view thereof, and the right side elevational view being substantially the same thereof;

FIG. 4 is a top plan view thereof; and,

FIG. 5 is a bottom plan view thereof.

The broken line showing of the connecting structure between the housing and the light kit and the down rod receiving opening are included for the purpose of illustrating environmental structure and forms no part of the claimed design.
